OCULAR POSITIONING DEVICE FOR AN EYE DROP DISPENSER

Gary J. Campagna, 236 Willow Ave., and Roland C. Janson, 114 Granada Drive, both of Corte Madera, Calif. 94925

Filed Nov. 21, 1974, Ser. No. 525,769

Term of patent 7 years

Int. Cl. D24—02

U.S. Cl. D83—1 N

Fig. 1

Fig. 2

Fig. 3

Fig. 4

Fig. 5

FIG. 1 is a front elevational view of an ocular positioning device for an eye drop dispenser, showing my new design;

FIG. 2 is a rear elevational view thereof;

FIG. 3 is a side elevational view thereof;

FIG. 4 is a top plan view thereof; and

FIG. 5 is a bottom plan view thereof.

We claim:

The ornamental design for an ocular positioning device for an eye drop dispenser, as shown.
